UNITED STATES PATENT OFFICE.

WALTER V. HARDY, OF INDIANOLA, MISSISSIPPI.

ELECTRIC STOVE.

1,118,763.

Specification of Letters Patent.

Patented Nov. 24, 1914.

Application filed August 19, 1914. Serial No. 357,500.

To all whom it may concern:

Be it known that I, WALTER V. HARDY, a citizen of the United States, and a resident of Indianola, in the county of Sunflower and State of Mississippi, have invented a new and useful Improvement in Electric Stoves, of which the following is a specification.

My invention is an improvement in electric stoves, and has for its object to provide a device of the character specified, especially adapted for heating press boxes, and wherein the arrangement is such that the stove may be placed within the box to heat the same, and wherein the box is provided with heating elements supported out of contact with the box.

In the drawings:—Figure 1 is a top plan view of the improved stove, Fig. 2 is a transverse vertical section, and Fig. 3 is an enlarged section on the line 3—3 of Fig. 1, looking in the direction of the arrows adjacent to the line.

The improved stove comprises a box or container of metal, consisting of a bottom 1, sides 2, and ends 3, the sides and ends being continuous.

Plates 4 of insulating material, as for instance, mica, are arranged transversely of the box in spaced relation and parallel therewith, each plate being supported by upper and lower pairs of lugs 5 at its ends. The lugs 5 are spaced apart from each other to receive the ends of the plates between the same, and each plate is spaced above the bottom 1 of the box and below the upper edges of the sides and ends, as clearly indicated in Fig. 2.

Each plate is provided with a longitudinal series of transverse openings 6, and the corresponding openings of all of the plates are in register. Strips 7 are arranged longitudinally of the box at the upper edges of the plates 4, the said strips 7 being parallel and spaced apart from each other, and the ends of the strips are connected to the ends of the box in any suitable or desired manner.

The plates 4 are notched to receive the strips, and the upper edges of the strips are flush with the upper edges of the plates. Coils 8 of resistance wire are arranged longitudinally of the box between the strips 7 and passing through the openings 6 of the plates 4. The strips 7 form a species

of grid at the top of the box, and the said strips are spaced apart at equal distances from each other and at the same distance from the sides 2.

One of the coils 8 is arranged between each adjacent pair of strips, and between the outermost strips and the sides 2 of the box, it being understood however, that the said coils are below the level of the strips and that the coils pass through the openings 6 of the plates. The coils 8 are connected at their ends in a manner to form a continuous coil.

The first coil at the right of Fig. 1 is connected to the second coil at the top of the said figure, by means of a coil 9, and the second coil is connected to the third coil at the opposite end of the box by means of a coil 10. The first coil at the left of the box is connected to the second coil at the top of Fig. 1, by a coil 9^a, corresponding to the coil 9, and the second coil is connected to the third coil at the bottom of the figure by a coil 10^a, corresponding to the coil 10. The central coils are connected at the top of the figure by a wire 11^a, and a lead wire 12 extends from the center of this wire through openings 13 in the plates 4 and through the opening in the opposite end of the box.

A wire 14 connects the outermost coil at the opposite end of the box from the wire 11, and a lead wire 15 leads from the center of the wire 14 out of the box. These wires 12 and 15 are the lead wires for supplying an electrical current to the coils. It will be noted from an inspection of Fig. 3 that the plates 4 are reinforced at their upper and lower edges by means of metal strips 16 and 17, which are bent in U-shape over the said upper and lower edges. The strips 16 and 17 extend from near one end of each plate to near the other end, and the plates are held in spaced relation above the bottom and below the strips 7.

The openings 6 in the plates 4 for the coils 8 are reinforced by metal sleeves or eyelets 18. Each of the sleeves or eyelets 18 is arranged within the opening, and the ends are expanded as shown to fit against the opposite faces of the plate.

The box proper is formed of metal of suitable weight. A lid is preferably provided for covering the box, the lid being shaped to fit on the top of the box. The bottom 1 is provided on its under face with longitudi-

nally extending ribs 19 for supporting the box out of contact with the surface upon which the box rests.

The notches for the strips 7 are in the reinforcing strips 16, and it will be noted from an inspection of Fig. 2 that the notches do not cut through the strips.

The improved stove is especially designed for use with press boxes, and the box or container of the stove is introduced directly into the box. The current is supplied to the resistance coils by way of the wires 12 and 15 and passing through the said coils they become highly heated and will heat the press box.

The current passes by way of the wire 13 and wire 14 to the outermost coils 8. Hence the current passes by way of the end coils 9 and 9^a to the adjacent coils, and by way of the coils 10 and 10^a to the innermost coils. From the innermost coils the current passes by way of the wires 11 and 12 to the source. The current is divided as it leaves the wire 15, passing in both directions and is again united at the wire 12. It will be evident that instead of wiring the coils in parallel, or dividing the current as above mentioned, the current may be supplied at one end and may pass out at the other, this being a matter of convenience. The strips 7 are braces for the insulating plates 4.

I claim:—

1. A device of the character specified, comprising a metallic box having supporting ribs on its bottom, transverse insulating plates supported in the box, said plates being held in spaced parallel relation, bracing strips arranged longitudinally of the box and extending from end to end thereof in spaced parallel relation, the said strips being at the upper edges of the insulating plates and being connected with the said plates to hold them in spaced relation, each of the insulating plates having transverse openings spaced apart at regular intervals,

a metallic eyelet at each of the said openings, the openings of the plates being in register, heating coils of resistance wire arranged longitudinally of the box in the openings of the insulating plates and supported by the plates, and an electric circuit in which the said coils are interposed, the upper and lower edges of the insulating plates being reinforced by metallic strips of U-shape fitting over the said edges and the uppermost strips of the plates being notched to receive the bracing strips.

2. A device of the character specified, comprising a box, transverse insulating plates supported in the box and held in spaced approximately parallel relation, each plate having a longitudinally extending series of openings, and the openings of all the plates registering, heating coils of resistance wire arranged longitudinally of the box in the openings of the insulating plates and supported by the said plates, an electrical circuit in which the coils are interposed, and bracing strips arranged longitudinally of the box at the upper edge of the plates and connected with the plates for holding them in spaced relation, said strips being arranged between adjacent coils.

3. A device of the character specified, comprising a box, transverse insulating plates supported in the box and held in spaced approximately parallel relation, each plate having a longitudinally extending series of openings, and the openings of all the plates registering, heating coils of resistance wire arranged longitudinally of the box in the openings of the insulating plates and supported by the said plates, an electrical circuit in which the coils are interposed, and reinforcing strips of U-shape fitting over the edges of the plates.

WALTER V. HARDY.
